J. T. CROWLEY.
APPARATUS FOR TREATING RUBBER ARTICLES.
APPLICATION FILED NOV. 10, 1916.

Patented May 15, 1917.

Inventor

John T. Crowley

Fraser, Turk Muses

UNITED STATES PATENT OFFICE.

JOHN T. CROWLEY, OF BEACON FALLS, CONNECTICUT, ASSIGNOR TO THE BEACON FALLS RUBBER SHOE COMPANY, OF BEACON FALLS, CONNECTICUT, A CORPORATION OF CONNECTICUT.

APPARATUS FOR TREATING RUBBER ARTICLES.

1,225,779.

Specification of Letters Patent. Patented May 15, 1917.

Application filed November 10, 1916. Serial No. 130,527.

To all whom it may concern:

Be it known that I, JOHN T. CROWLEY, a citizen of the United States of America, residing in Beacon Falls, in the county of 5 New Haven and State of Connecticut, have invented certain new and useful Improvements in Apparatus for Treating Rubber Articles, of which the following is a specification.

0 This invention relates to the vulcanization of hollow rubber articles, and has for an object to provide suitable apparatus whereby the article under treatment is caused to closely hug the form on which it is cured, 5 the various plies of the article, if this is of a built up structure, are closely drawn together and united, and, if the article is formed with a fabric lining—such as an article of footwear, the outer portion is 0 closely drawn into union with the lining and the entire article caused to conform to the last, and whereby the mass of the article is freed from occluded gases and volatile substances and closely compacted, and all 5 gases and vapor generated within and upon the form are removed.

This invention, although capable of general application, is peculiarly adapted to the vulcanization of rubber footwear on wooden 0 lasts in dry heat.

Heretofore it has been proposed to vulcanize hollow rubber articles by mounting them on suitable forms and sealing the free edge of the article to the form and subjecting 5 the respective sides of the article to differential pressures during vulcanization. In these differential pressure processes it has always been necessary to furnish a seal or 0 dam whereby the higher pressure on the outer side will not be communicated to the inner or form side of the article in communication with the lower pressure. According to this present invention such sealing 5 is not necessary, although the inner side of the article is communicated with the lower pressure.

In using my invention the hollow article to be vulcanized is placed upon or built around, as the case may be, the pervious form, and differential pressures are applied 0 to the respective sides of the article during at least the early portions of the heat treatment, the interior of the form being connect-

ed with a lower pressure than that upon the outer side of the article.

55

It is also part of my invention in the manufacture of footwear, for instance, rubber overshoes having a fabric lining, to provide a chamber within the pervious last extending toward those portions of the last 60 where there are cavities or depressions, as for instance, at the juncture of the heel with the sole, so that the differential pressure causes the shoe to closely hug the last and draw all the plies of rubber and fabric together. This invention does away with a great deal of the hand work now individually bestowed upon each article of rubber 65 footwear. It also permits of a cheap and rapid manufacture or building up of the 70 article, in that it can be built up upon the ordinary wooden last without recourse to seals and dams at the top edge.

In the use of wooden lasts great difficulty is experienced in dry heat processes, particularly in the open oven process, from the moisture which gets in or upon the lasts during certain climatic conditions. When these 75 climatic conditions exist, particularly in certain seasons of the year, moisture either in fluid form or as a gas, is generated from the lasts and has a tendency to injure the article being treated, and also prevents it closely adhering to the surface of the last. This objectionable feature is completely 80 done away with in my present improvement.

Reference is made to the accompanying drawings, showing an example of the apparatus which I have found useful in practice, 85 wherein,

90

Figure 1 is a sectional view showing an illustrative example of a pervious form having upon it a rubber article, and

Fig. 2 is a longitudinal sectional view of a pervious last having mounted thereon a 95 rubber shoe.

In carrying out my invention a form for the hollow article to be vulcanized is provided. This form is made of some suitable porous material, as, for instance, plaster 100 molded in some suitable form, an example of which is illustrated at 5 in Fig. 1, or pervious wood is used, an example of which is illustrated at 6 in Fig. 2. The article is either formed and placed upon the form or 105 last or is built up on it. When the im-

proved form is used in connection with rubber footwear, the article is built up upon the last in the usual manner. After the article is properly placed upon or built 5 around the form, the article and form are placed in a suitable vulcanizing chamber and subjected to a suitable vulcanizing medium, preferably dry gas, and the interior of the pervious form is placed in communication with fluid pressure lower than the 10 fluid pressure of the vulcanizing medium. The effect of this differential in pressures is to first draw from the form all vapor or gases which otherwise would have a tendency 15 to work toward the surface of the form incident to the heat to which it is subjected in the vulcanizing chamber. The lower fluid pressure within the pervious form also tends to draw the article under 20 treatment closely against the form throughout its entire contour.

The porous form employed by me, whether a wooden last or some other porous material, presents upon its surface a myriad 25 of mouths which communicate the lower pressure to the entire inner surface of the hollow article undergoing treatment.

For the better application of the lower fluid pressure to the interior of the article, 30 this is preferably cored out thereby providing a chamber adapted to be placed in communication with a source of lower pressure than that existing within the vulcanizing chamber and applied to the exterior 35 of the article. This low pressure chamber preferably passes in the region of, or approaches the deeper depressions or cavities of the mold surface. In Fig. 1, at the plane on which the cross-section of the form 5 is 40 taken, there is at the portion farthest from the base an enlargement, and between such portion and the base there is a contracted or neck-like portion 7. The rubber article in this figure is designated by the reference 45 character 8, and will be assumed to be formed in any desired or well known manner of making hollow rubber articles. The chamber 9 within the form, illustrated in this figure, extends into the enlarged portion 50 and is so located relatively to the neck portion 7 that the overlying rubber article receives the full benefit of lower fluid pressure within such chamber 9 than that presented by the vulcanizing medium to the exterior of the article. One feature of my 55 invention is to dispose the low pressure or suction chamber adjacent those portions of the form away from which the rubber article is inclined to move, and also adjacent the 60 cavities of the form into which it is difficult to force the rubber in the building up operation.

The form 7 in Fig. 1 is shown resting upon the outer surface of a table 10, such 65 table being shown provided with a chamber

11 having an opening 12 registering with the chamber 9 when the form is in proper position upon the table. A conduit 13 is shown leading from the chamber 11, such conduit being assumed to be connected to some suitable source of low pressure, as, for instance, a vacuum pump. For certain classes of work a plaster or cement form is quite desirable. In other classes of work, however, such as, for instance, the commercial manufacture of rubber footwear, wooden lasts are more desirable, particularly when the vulcanizing medium is dry heat. Such a last is shown in Fig. 2, represented by the reference character 6. This last is 70 assumed to be the ordinary wooden last, preferably made of maple wood. A rubber overshoe illustrated in a conventional manner is shown mounted upon this last. Although the rubber shoes may, and generally 75 will be, built up according to the usual practice of rubber shoe building, yet for simplicity in the present illustration it is shown with an outer layer of rubber 14 upon a fabric lining 15, which lining is interposed 80 between the layer of fabric and the last or form.

The most convenient manner of applying the lower pressure to the interior of the commercial wooden last is to bore a hole 16 in the top of the last and permit this hole, which constitutes a chamber, to extend a suitable distance beyond the top edge of the rubber overshoe. To prevent leakage from the chamber 16 through that portion of the 10 last which is not covered with the rubber article, an impervious sleeve 21 may be inserted into the bore 16 and extend upwardly a slight distance beyond the upper edge of the overshoe. The outer end of the bore 16 is shown flaring to better receive and hold the tapering sleeve illustrated. This sleeve 15 may also constitute a portion of a connection with a suitable source of low pressure, as, for instance, it may be slightly flaring interiorly and adapted to fit a tapered nipple 22 carried by a conduit 23 extending to the atmosphere or to a suction pump. The sleeve 21 is shown provided with a flange 24. The flange is illustrated as having a notch 25 registering with a lug 26 to properly position the last upon the conduit, which in present practice will constitute a rack or bar for supporting a plurality of the articles in the vulcanizing chamber in a well known manner.

It is to be noted that the upper portion of the overshoe indicated by the reference character 27 need not be sealed to the form or last, nor need the exposed portions of the last be insulated.

The low pressure chamber preferably extends an appreciable distance within the last and may extend well into the heel and adjacent the portion 17, which represents the

angle between the front of the heel and the instep portion of the sole. This extension of the chamber is represented by the reference character 16'. In certain cases it is also 5 desirable to extend the low pressure chamber throughout practically the entire length of the last. This can conveniently be effected by a transverse bore, as 18, projecting from the heel toward the toe of the last, and 10 also passing adjacent the region of the depression 19 between the toe and the instep portions. This transverse bore 18 may enter the back of the last and be closed by a suitable, but preferably pervious, plug 20.

15 As an illustrative example of the operation of my invention, the manufacture of a rubber shoe is herein described. Of course, it is to be understood that the invention is not limited either to rubber shoes or other 20 articles of footwear, but is applicable to various hollow rubber articles. For making the wooden form for use in the treatment of rubber overshoes, which form in the illustrative example is a last 6, some suitable 25 permeable wood is selected. In fact, most of the woods now employed for lasts for the manufacture of rubber footwear are suitable for this purpose. Maple is quite generally employed for lasts used in the large rubber 30 factories. Hardness or density of the wood, so long as it is sufficiently permeable for the carrying out of the process, is a desirable feature. The last is given the desired form 35 exteriorly to produce the proper shape of finished overshoe, and this last is provided with means for communicating its interior with a fluid pressure lower than that which is to be exerted upon the outer side of the shoe by the vulcanizing medium. The form 40 and details of a practicable arrangement of interior spaces are set forth in the above description with particularity. The rubber shoe is built up in any desired manner upon the last, preferably with a fabric lining in 45 communication with the surface of the last. Attention was above called to the fact that it is not necessary to seal the edge 27 of the article to the form.

In building up the overshoe the workman 50 need not be particular to secure an intimate connection between the various plies of fabric, nor to force the built up article completely into the cavities and depressions of the last. After the overshoe has been built 55 up the last is connected with the source of lower pressure, in the present illustration by being mounted upon the nipple 22 carried by the pipe 23. This pipe may, if desired, carry a large number of shoes, and 60 with them be placed into the vulcanizer. If the vulcanizing medium is heated air at about atmospheric pressure in the open heat

vulcanizing system, the pipe 23 is connected to a suitable suction pump. The open oven treatment requires about seven hours for 65 vulcanizing overshoes, and it has been found desirable to maintain the suction during the first three or four hours of the curing process. If the vulcanizing medium is applied under pressure within a closed vulcanizing chamber, it will be sufficient to connect the interior of the last with the atmosphere, either during the earlier stages of the application of the vulcanizing medium, or, if desirable, through the entire period. Owing 70 to the fact that the preferable material for making the forms is wood, the vulcanizing medium should be a dry gas. After vulcanization it is found that the overshoe is free from blisters and open spaces, and that 75 the rubber stock is compacted, particularly at the heel, and that the entire thickness of the article has been drawn closely down into the depressions of the last.

What I claim is:—

1. A porous wooden last having a chamber within the foot portion and means for communicating the said chamber with a source of low fluid pressure.
2. A solid last of porous material having 90 a chamber within it, the walls being thinnest near the concave portions of the exterior where the greatest suction effect is required, and means for communicating such chamber with a source of low fluid pressure.
3. A last for rubber footwear of porous material having a chamber with portions approaching the juncture between the heel portion and the sole portion, and the incurve 100 between the instep portion and the toe portion, and means for connecting the said chamber with a source of low pressure.
4. A form comprising a wooden last having a bore extending from its upper portion toward the heel and a bore extending longitudinally of the last, and means for connecting said bores with a desired condition of fluid pressure.
5. A form comprising a wooden last having a bore extending from its upper portion 110 toward the heel and adjacent the juncture between the heel portion and the sole portion, and a bore extending longitudinally of the last and adjacent the in-curve between the instep portion and the toe portion, and 115 means for connecting said bores with a desired condition of fluid pressure.

In witness whereof, I have hereunto signed my name in the presence of two subscribing witnesses.

JOHN T. CROWLEY.
